UNITED STATES PATENT OFFICE.

EDWIN J. SWIFT, OF SHEEPSHEAD BAY, NEW YORK.

CARTON HOLDER AND FILLER.

Application filed March 29, 1924. Serial No. 702,929.

To all whom it may concern:

Be it known that I, EDWIN J. SWIFT, a subject of the King of England, residing at Sheepshead Bay, in the county of Kings 5 and State of New York, have invented certain new and useful Improvements in Carton Holders and Fillers, of which the following is a specification.

This invention relates to an improved 10 carton holder and filler, particularly adapted for use in dispensing ice cream, butter, lard and other plastic substances.

One of the objects of my invention is to provide a carton filling device or apparatus adapted to cut into a semi-hard plastic mass, such as ice cream and the like so as to completely fill the interior of a carton.

Another object of my invention is the 20 provision of a carton filling device or apparatus wherein the interior of the carton to be filled is urged or pressed into the plastic composition or substance in an inverted position and subsequently removed 25 therefrom by gravity when the apparatus or device is inverted and the handles thereof opened outwardly.

To enable others skilled in the art to 30 fully comprehend the underlying features of my invention, that they may embody the same in the various modifications in structure and relation contemplated, drawings depicting a preferred form have been annexed as a part of this disclosure, and in 35 such drawings, similar reference characters denote corresponding parts throughout all the views, of which,

Figure 1 is a perspective view of the 40 measuring and carton filler as preferably constructed.

Figure 2 is an inverted side view showing the filled carton being ejected by gravity as the handles are opened outwardly.

Figure 3 is an enlarged, fragmentary sectional view showing the relation of the container to the carton.

Referring now to the drawings wherein like reference characters designate corresponding parts throughout the several 50 views, 5, 6, designate the sides, and 7 the ends of a substantially rectangular carton container or casing, preferably constructed of metal. The said carton container or casing is open at the top 8 and bottom 9, 55 it being slightly larger than the card board or paper carton 10 which is to be filled,

the said carton being of a type as is commonly used in the sale of ice cream, butter, lard and other food products of plastic form.

The bottom edges and ends of the carton container casing are bevelled as indicated at 11, so as to easily cut through the plastic mass, being also formed with an interior ledge or shoulder 12, on which the inverted carton 10 is positioned as clearly shown by Figure 3 of the drawings. In order to facilitate the cutting of the plastic mass, as the inverted carton within the container is forced into the same, I have also 60 provided an auxiliary cutter 13, positioned intermediate the sides of the container so that less pressure is necessary to urge the device and the carton into the plastic mass, completely filling the said carton. If so 65 desired, two or more cutting knives may be positioned between the sides, at the bottom thereof or between the ends, of the container, where a larger carton measuring 70 device or apparatus is desired. This auxiliary cutter also serves the purpose of a cutting off device between the contents of the carton and the main mass, which is 75 effected by a slight rocking movement or partial rotation of the whole device by the manipulation of the handles but in the 80 small sized apparatus but a single cutter is sufficient for the above purpose.

Pivottally connected to the ears 14, 15, on the sides 5, 6, of the container, I have 85 provided a yoke-shaped frame 16 on each side of the apparatus or device, each of said frames being provided with a handle 17 of any desired length or shape for manipulating the apparatus or device in both 90 filling the carton and ejecting the same when completely filled. Each yoke frame 95 16 is pivotally connected as at 18 to the respective ears which are positioned at the corners and preferably near the top of the 100 container. A pair of angularly disposed stops 19 are provided to also limit the outward movement of the said frames with respect to the container as when ejecting 105 the filled carton, in the manner shown by Figure 2 of the drawings, whereby as the handles are moved outwardly, the filled carton may be ejected by gravity. The outer edges of the stops are cut so that the 110 top edges permit the frames 16 to rest flush against the same when the said frames are in a vertical position.

Between the sides of each of the yoke frames 16, there is provided, what I term a skirt 20, preferably of thin, light metal, which prevents the percolation of the substance from the main mass over the top of said container. The vase 21 of the skirt is preferably bent inward to also prevent the substance from percolating through and between the frame and the skirt proper.

Referring to Figure 1 in particular, it will be seen that I have provided a spindle 23, positioned between the sides of each frame 16, which spindle is also secured by a metal strap attachment 24^a to the inner side 15 of the skirt, heretofore referred to. Extending inwardly and at right angles to the skirt of each frame 16, I have provided a metal flap 24, 25 preferably rectangular in form, which completely closes over the top 28 8 of the container, when the said frames are closed by being moved toward each other as the handles are manipulated and brought to a vertical position with respect to the container. Each of the flaps are provided with 25 a slight central depression 26, which is adapted to bear against the inverted base 27 of the interior carton so as to press down the carton in its inverted position to rest on the ledge or shoulder 12 inside the bottom 32 edges of the sides and ends as heretofore referred to.

In the operation of the device, as the handles 17 are moved outwardly to their maximum position and the flaps uncover the open 25 top of the container, the carton with its cover flap folded toward its side is inverted and inserted within the said container so as to rest on the shoulders or ledges 12 adjacent the bottom. The handles and the 40 frames 16 are then moved toward each other until in a vertical position so that the inner edges of the flaps 24, 25, will engage each other, in which position, the device may be forced up to the edges of the container into the plastic mass, completely filling the said inverted carton. The cut off from the main mass is effected by a slight rocking movement of the whole device as the handles are manipulated. The filled carton may be removed by simply inverting the whole device and opening the frames 16 so that by moving the same outwardly, as shown by Figure 2, the filled carton will be ejected by gravity as clearly understood and will fall out on 55 its own base.

It will of course be recognized that the device lends itself for use in connection with practically any semi-solid or plastic composition and is capable of being manufactured in various sizes and material to accommodate various types of cartons, that is to say, either square, rectangular or round. Of course, the container proper must be shaped to conform to the type or design of 60 65 carton to be used and necessarily the flaps

24, 25 must be altered to exactly fit the open top of the particular shaped container desired.

Having thus described my invention, what I claim as new and desire to secure by United States Letters Patent is:—

1. A carton filling device comprising a container open at its top and bottom, means for supporting an open carton in an inverted position within the container, a pair of frames pivoted to said container and having means for closing the open top and engaging the bottom of the carton whereby the said container and the inverted carton may be forced into a plastic mass.

2. A carton filling device comprising a container open at its top and bottom, means adjacent the bottom of the container for supporting an open carton in an inverted position within the container, a pair of complementary manually operable frames pivoted to the container, a flap attached to each frame for closing the open top of the container in one position whereby the said container and the carton may be forced into a plastic mass, said frames and flaps being movable to an open position whereby the filled carton may be ejected by gravity as the said container is inverted.

3. A carton filling device comprising a container open at its top and bottom, means for supporting an open carton in an inverted position within the container, a pair of frames pivoted to the container, means for limiting the inward and outward movement of said frames, flaps attached to the said frames for closing the open top of the container whereby the latter and the said carton may be forced into a plastic mass.

4. A carton filling device comprising a container open at its top and bottom, means for supporting an open carton in an inverted position within the container, a pair of frames pivoted to the container, stops for limiting the inward and outward movement of the frames, a skirt connecting the sides of each frame, a flap attached to each skirt and adapted to close the top of the container as the said frames are moved to their inward position, whereby said carton and container may be forced into a plastic mass.

5. A carton filling device comprising a container open at its top and bottom, means for supporting an open carton in an inverted position within the container, and means pivoted to the sides of the container for closing the open top in one position whereby the carton may be forced into a plastic mass for filling, said means being movable to an open position with respect to the container whereby the filled carton may be ejected by gravity as said container is inverted.

6. A carton filling device comprising a container open at its top and bottom, the

lower edges of the container being bevelled and having a ledge on the interior surfaces thereof for supporting an open carton in an inverted position, a knife blade positioned between the ends of the container adjacent its bottom, ears attached to the sides of the container, a pair of yoke frames pivoted to the said ears, flaps attached to the frames for closing the open top of the container, 10 said frames being movable inwardly and outwardly with respect to the container to close and open the top thereof whereby the inverted carton may be forced into a plastic mass.

15 7. A carton filling device comprising a container open at its top and bottom, the

lower edges of the container being bevelled and having an interior ledge for supporting an open, inverted carton, a knife blade positioned between the ends of the container adjacent its bottom, a pair of yoke shaped frames having handles pivoted to the sides of the container, flaps attached to the frames for closing the open top of the container when the frames are moved toward each other, 20 said frames being movable outwardly with the flaps to permit the filled carton to drop by gravity as the said container is inverted.

In testimony whereof I affix my signature.

EDWIN J. SWIFT.
